FOWL RACK

Carl J. Ellis, Lancaster, Wis.

Application November 16, 1935, Serial No. 50,199

2 Claims. (Cl. 17—11)

The invention relates to a fowl rack and more especially to a testing and vaccinating rack for chickens.

The primary object of the invention is the provision of a rack of this character, wherein a chicken to be operated on can be readily and easily placed and held in position for the operation, the rack being of novel construction for convenient access to the spine of the cockerel to allow caponizing in a humanely manner.

Another object of the invention is the provision of a rack of this character, wherein the neck, wings, body and legs can be clamped for the holding of the fowl to eliminate motion so that such fowl can be operated upon or tested with ease.

A further object of the invention is the provision of a rack of this character, which is extremely simple in construction, thoroughly reliable and efficient in its purpose, strong, durable, easily handled, holding the fowl motionless, and inexpensive to manufacture.

With these and other objects in view the invention consists in the features of construction, combination and arrangement of parts as will be hereinafter more fully described, illustrated in the accompanying drawing, which discloses the preferred embodiment of the invention and pointed out in the claims hereunto appended.

30 In the accompanying drawing:—

Figure 1 is a perspective view of the rack constructed in accordance with the invention showing a fowl held therein.

Figure 2 is a perspective view of the rack in closed position with the fowl removed.

Figure 3 is a side elevation showing by full lines the rack in its closed position and by dotted lines the rack in its open position.

Similar reference characters indicate corresponding parts throughout the several views in the drawing.

Referring to the drawing in detail A designates generally a flat board-like section providing an operating slab or block 5, preferably square in formation and of a size to accommodate varying sizes of fowls. Intermediate of this slab or block 5 at opposite side edges are brackets 6 and 7, respectively, each formed from a single length of relatively rigid wire. The wire forming the bracket 6 is bent on itself to provide a central substantially U-shaped neck yoke 8,

while the wire forming the bracket 7 is bent on itself to provide a double substantially U-shaped leg yoke 9, these brackets being secured in the slab or block 5 at their ends 10 to be upstanding from the top face of said slab or block.

Between the brackets 6 and 7 swings a clamp 11 formed into a wire frame having neck, wing, tail, leg and body loops 11, 12, 13, 14, and 15, respectively, these being of special or required formation to bridge in their order the neck, wings, tail, legs and body of a fowl identified at 16, when laid on the slab or block 5 upon its side on the closing of the clamp 11. This clamp 11 is hinged for opening and closing movements through the medium of staples 17 these straddling the pivotal end portions 18 of the wire frame forming the said clamp and are driven into the slab or block 5 as is clearly shown in Figures 1, 2, and 3 of the drawing.

The fowl 16 when held by the clamp 11 on the closing of the latter with relation to the slab or block 5 will be gripped in a fashion to be rendered motionless so that said fowl can be operated upon for caponizing or vaccination or for testing purposes as may be required.

The clamp 11 when closed onto the slab or block 5 is fastened in this position by a turning latch 19.

The rack is also useful for testing fowls for pullorum diseases, tuberculosis, legbanding and capsuling or for other purposes and any number may be supported upon a suitable size slab or block.

What is claimed is:

1. A rack of the kind described, comprising a slab, opposed brackets carried by said slab and forming yokes for accommodating the neck and legs of a fowl, and a swinging clamp movable between the said brackets and having neck, wings, tail and body loop portions for bridging like parts of the fowl.

2. A rack of the kind described, comprising a slab opposed brackets rising from the upper face of said slab and forming yokes for accommodating the neck and legs of a fowl, a swinging clamp working between the brackets and having neck, legs, wings, tail and body loops for bridging like parts of a fowl, means swingingly connecting the clamp with the slab, and means for latching the clamp engaged with the fowl.

CARL J. ELLIS.
